INVENTOR

WM. J. BIEN

BY *E. G. Chapman*
ATTORNEY

UNITED STATES PATENT OFFICE.

WILLIAM J. BIEN, OF BELLEVILLE, ILLINOIS, ASSIGNOR TO BELLEVILLE CASKET COMPANY, OF BELLEVILLE, ILLINOIS, A CORPORATION OF ILLINOIS.

BURIAL CASKET.

Application filed December 21, 1922. Serial No. 608,195.

To all whom it may concern:

Be it known that I, WILLIAM J. BIEN, a subject of the United States of America, residing at the city of Belleville, State of Illinois, United States of America, have invented certain new and useful Burial Caskets, of which the following is such a full, clear, and exact description as will enable any one skilled in the art to which it applies to make and use the same, reference being had to the accompanying drawings, forming part of this specification.

My invention relates to a burial casket and has for its object the provision of means for illuminating the interior of the casket, which means comprises a source of light and a collapsible canopy for directing the rays of light from the source, said canopy preferably forming a portion of the casket decoration.

In the accompanying drawings which illustrate one form of casket made in accordance with my invention, Fig. 1 is a front elevation, Fig. 2 is a vertical section through the lid or panel and Fig. 3 is a diagrammatic view.

5 indicates the body of the casket and 6 the lid or panel which is hinged to the body of the casket at 7 so that it may be swung upwardly into a substantially vertical position as shown. The panel is retained in position by any suitable means, such, for example, as the cord 8 shown in Fig. 1. The face of the panel 6 is covered with textile material 9, such as puffed satin so arranged as to produce a decorative effect. The covering 9 is provided with a loose portion 10 cooperating with an enclosed curved rod 11 to produce a collapsible canopy forming a part of the decoration of the casket. The rod 11 is pivoted to the panel 6 at the points 12 so that it will fall down by gravity into the position shown in Fig. 2, when the panel is raised, carry-

ing with it the loose portion 10 of the material 9. Arranged just below the canopy 10, preferably at its central part is an incandescent lamp 13 which may be supplied with current through the circuit 14 from any suitable source, such as the battery 15 contained in a receptacle 16 within the casket.

The canopy 10 not only screens the lamp 13 from the direct view of the observer but also acts as a reflector to direct the rays of light downwardly and forwardly into the casket, thus producing the maximum amount of light at the point desired. When the panel 6 is lowered, the canopy 10 is free to fold back against the panel.

Having fully described my invention, what I claim as new and desire to secure by Letters Patent of the United States is:

1. In a burial casket, the combination with the body of the casket, of a panel, a source of light carried by said panel, and a collapsible canopy of flexible material also carried by said panel for reflecting the rays from said source of light forwardly and downwardly.

2. In a burial casket, the combination with the body of the casket, of a panel, a source of light carried by said panel, a textile covering for said panel, and a canopy forming a part of said covering and adapted to direct the rays from said source of light downwardly and forwardly.

3. In a burial casket, the combination with the body of the casket, of a panel, a source of light carried by said panel, a textile covering for said panel including a loose fold, and a pivoted rod in said fold adapted to extend the same to form a canopy for directing the rays from said source forwardly and downwardly.

In testimony whereof, I have hereunto set my hand and affixed my seal.

WILLIAM J. BIEN. [L.S.]
